SWITCH MECHANISM FOR A COUNTER

Lester W. Norell and Harry A. Sowle,
San Francisco, Calif.

Application May 20, 1952, Serial No. 288,788

7 Claims. (Cl. 200—61.42)

The present invention relates to a switch mechanism for a counter intended particularly for counting the sheets in a stack of paper.

More particularly it is proposed to provide a switch mechanism of the character described which includes a needle point adapted for guiding over the edges of a stack of paper sheets, with the edges arranged in stepped relation.

It is further proposed to provide a switch mechanism of the character described that is very sensitive and quick in its reaction so as to open and close in synchronism with the vibrations imparted to the point of the needle as the latter is guided over the stepped edges.

As the needle point is thus guided to descend along the steps formed by the edges of the sheets of paper, it is placed under tension as long as it rests on an edge of a sheet of paper and is released as it moves from one step to the next one. If this movement is carried on with a desired degree of speed, the needle point is set into vibratory motion, one vibration for each step, and it is the object of the present invention to provide for a switch mechanism which opens and closes a switch in response to the vibratory movement of the needle point so that the switch opening and closing movements correspond exactly to the vibratory movement of the needle point and to the number of steps along which the needle point descends.

For this purpose it is intended to provide a switch mechanism which may be easily operated, is convenient in handling and is very sensitive and accurate in its response to the movements of the needle point.

Further objects and advantages of our invention will appear as the specification proceeds, and the novel features of our invention will be fully defined in the claims attached hereto.

The preferred form of our invention is illustrated in the accompanying drawing, in which

Figure 1 shows a horizontal section through the switch mechanism, taken immediately underneath the cover of the latter,

Figure 2, a vertical section through the switch mechanism,

Figure 3, a front view of our device,

Figure 4, a section taken along line 4—4 of Figure 2,

Figure 5, a section taken along line 5—5 of Figure 2, and

Figure 6, an enlarged detail view illustrating the principal working characteristics of the invention.

While we have shown only the preferred form of our invention, we wish to have it understood that various changes and modifications may be made within the scope of the claims attached hereto without departing from the spirit of the invention.

Referring to the drawing in detail, our switch mechanism comprises in its principal features a housing 1, a needle 2 pivoted therein as at 3 and having a switch 4 carried thereby, a spring 5 mounted in the housing, and a hammer 6 operable by the spring 5 for opening the switch 4 in response to vibratory movement of the needle point indicated at 7.

The housing 1 may be made in any suitable shape and is here shown in the form of a tube rectangular in cross-section and rather elongated in form. It should be noted that Figures 1 and 2 show our device on a scale of two to one and that in the views of Figures 3 to 5 inclusive the proportions have again been doubled.

The needle 2 is preferably made of metallic material

2

and carries, at its forward end, a triangular block 8 mounted in the front end of the tube, the block 8 carrying the pivots 3 which are journaled in the side walls of the tube. The point 7 of the needle projects only slightly beyond the front end of the tube, as clearly shown in Figures 1 and 2.

The main body portion of the needle 2 and its rear portion project through the major length of the tube or housing, and the rear end of the needle terminates in a vertical flange 9 forming part of the switch 4. An intermediate section of the needle carries a block 10, between insulating members 11, and a spring 12 has one end secured upon the block as at 13 while its rear end terminates in a contact 14 cooperating with the flange 9 in forming the switch 4. Intermediate the block 10 and the flange 9, the needle carries a cylindrical element 15 which projects above and below the upper and lower surfaces of the needle respectively.

The block 10 on the needle has the hammer 6 pivoted thereto as at 16, the hammer comprising a handle or rod 17 and a head or weight 18, the latter being preferably made in sections so as to allow the weight to be decreased or increased for better response to the vibratory movement. The far end of the hammer is disposed underneath the free end of the leaf spring 12 so that an upward movement of the weight strikes the free end of the spring 12 and lifts the contact 14 off the flange 9 for opening the switch. The handle or rod 17 of the hammer normally rests on the cylindrical body 15.

The spring 5 runs parallel to the bottom 19 of the tube or housing and is anchored to the tube at the rear end thereof as at 20, in slightly spaced relation to the bottom. The forward end of this leaf spring extends underneath the rear end of the needle and supports the cylindrical member 15, and through the latter, the rear end of the needle.

A stop 21 limits the upward swing of the main body portion of the needle 2.

Electrical connections 22 and 23 may be anchored on opposite sides of the switch as at 13 and 20.

In operation the device may be handled very much like a comparatively short pencil to which it substantially corresponds in dimensions. The point 7 is made to descend a stack of sheets of paper having its edges arranged in stepped relation. This will set up a vibratory movement in the point of the needle corresponding exactly to the number of steps over which it passes. As the point of the needle presses on one of the steps the rear section is urged downward, and as the point drops from one step to the next one the pressure is released and the rear portion of the needle is free to move upward.

During the pressure period the cylindrical body 15 bears on the front end of the leaf spring 5 and places the latter under tension. As the tension is released due to the movement of the needle point from one step to the next one, the front end of the spring 5 rebounds and, through the cylindrical body 15, throws the hammer 6 upward, which latter again strikes the free end of the spring 12 and separates the contact portion from the flange 9 so as to open the switch 4. As the needle point is again placed under pressure by coming to rest on the next step, the cylindrical body 15 again bears on the front end of the leaf spring 5 and allows the hammer 6 to return to its original position, thereby allowing the switch 4 to close.

The counter to be used in connection with this switch mechanism may be of any suitable standard form and is not illustrated in the drawing. In its preferred form it would include a rotary member for operating a meter over a dial and the rotary member would be operated by a pawl and ratchet arrangement, the pawl being operated in one direction by an electro-magnet having the switch 4 incorporated in the circuit thereof, and in the other direction by a suitable spring operating in opposition to the electro-magnet.

We claim:

1. In a counter for a stack of sheets having edges arranged in stepped relation, an elongated housing, a needle pivoted in the front end of the housing and having a point extending forwardly of the housing and a long end extending rearwardly into the housing and having

an upward flange at the rear end thereof adapted to form a switch contact, a block carried by the needle at an intermediate section thereof and having a leaf spring mounted thereon, the leaf spring extending rearwardly and having a rear end normally bearing on the flange to form a switch therewith, a second leaf spring mounted in the rear end of the housing in slightly spaced relation to the floor thereof and having a front end extending under a rear section of the needle, a spacing means on the needle bearing on the front end of the second leaf spring for normally holding the needle and the second leaf spring in slightly spaced relation, and also extending above the needle, and a rod pivoted in the block and extending rearwardly therefrom and having a head disposed underneath the first leaf spring and between the spacing means and the flange, whereby when the point of the needle is pressed upon the edge of a sheet of paper, the spacing means is made to depress the second leaf spring for placing the latter under tension, and when the needle point is made to slide off the edge, the second leaf spring causes the spacing means to flex against the rod for causing the head to flex against the first leaf spring for opening the switch.

2. In a counter for a stack of sheets having edges arranged in stepped relation, an elongated housing, a needle pivoted in the front end of the housing and having a point extending forwardly of the housing and a rear end extending into the housing and having an upward flange at the rear end thereof adapted to form a switch contact, a block carried by the needle at an intermediate section thereof and having a leaf spring mounted thereon, with the end of the leaf spring normally bearing on the flange to form a switch therewith, a second spring in the housing adapted for being placed under tension by the needle when the point of the latter is pressed upon a sheet edge, and a hammer pivoted in the block and operable by the second spring for being thrust against the first spring for opening the switch when the second spring is released due to the sliding off of the needle point from the sheet edge.

3. In a counter for a stack of sheets having edges arranged in stepped relation, an elongated housing, a needle pivoted in the front end of the housing and having a point extending forwardly of the housing and a rear end extending into the housing, a switch carried by the rear end of the needle, a spring mounted in the housing and operable for being placed under tension by the needle when the point of the latter is pressed upon a sheet edge, and means arranged immediately adjacent the switch and operable by the rebound of the spring for opening the switch when the tension of the spring is released to the sliding off of the needle point from the sheet edge.

4. In a counter for a stack of sheets having edges arranged in stepped relation, an elongated housing, a needle pivoted in the front end of the housing and having a point extending forwardly of the housing and a rear end extending into the housing, a switch carried by the rear end of the needle, a spring mounted in the housing and operable for being placed under tension by the needle when the point of the latter is pressed upon a

sheet edge, and means arranged immediately adjacent the switch and operable by the rebound of the spring for opening the switch when the tension of the spring is released to the sliding off of the needle point from the sheet edge, the latter means including a freely pivoted member acted on by the spring to accelerate the switch opening movement.

5. In a counter for a stack of sheets having edges arranged in stepped relation, an elongated housing, a needle pivoted in the front of the housing and having a point extending forward of the housing and a rear end extending into the housing and having a contact member at the rear end, a leaf spring mounted on the needle having a rear end normally bearing on the contact member, a second spring in the housing adapted for being placed under tension by the needle when the point of the latter is pressed upon a sheet, and a hammer pivoted with respect to the needle and operable by the second spring for being thrust against the first spring to separate the same from the contact member when the second spring is released due to the sliding off of the needle point from the sheet edge.

6. In a counter for a stack of sheets having edges arranged in stepped relation, an elongated housing, a needle pivoted in the front of the housing and having a point extending forward of the housing and a rear end extending into the housing and having a contact member at the rear end, a leaf spring mounted on the needle having a rear end normally bearing on the contact member, a second spring in the housing adapted for being placed under tension by the needle when the point of the latter is pressed upon a sheet, and means movable with respect to the needle and operable by the second spring for being thrust against the first spring to separate the same from the contact member when the second spring is released due to the sliding off of the needle point from the sheet edge.

7. In a counter for a stack of sheets having edges arranged in stepped relation, an elongated housing, a needle pivoted in the front of the housing and having a point extending forward of the housing and a rear end extending into the housing and having a contact member at the rear end, a leaf spring mounted on the needle having a rear end normally bearing on the contact member, a second spring in the housing adapted for being placed under tension by the needle when the point of the latter is pressed upon a sheet, and means movable with respect to the needle and operable by the second spring for being thrust against the first spring to separate the same from the contact member when the second spring is released due to the sliding off of the needle point from the sheet edge, the said means being active on the first spring immediately adjacent the contact member.
